UNITED STATES PATENT OFFICE.

DALLAS H. SMITH, OF MARICOPA, ARIZONA.

GRADE-CROSSING CONTROL.

Application filed October 12, 1922. Serial No. 593,949.

To all whom it may concern:

Be it known that I, DALLAS H. SMITH, a citizen of the United States, residing at Maricopa, in the county of Pinal and State of Arizona, have invented new and useful Improvements in Grade-Crossing Controls, of which the following is a specification.

This invention relates to grade crossing controls and has for its object to provide automatically operative barriers for retarding or preventing the running of a road vehicle onto and across a railroad track at grade crossings.

Another object of the invention is to provide grade crossing barriers which are controlled, preferably electrically, by the entry of a rolling stock of railroad systems into a zone extending a suitable distance in either direction from the line of the highway or road crossing.

Another object of the invention is to provide barrier means rendered effective to retard the advance of a vehicle coming toward the railroad tracks and yet operative to permit the passage of a vehicle over the barriers when leaving the railroad tracks.

Another object is to provide a barrier actuating means including adjacent devices one operative yieldingly by the passage of a road vehicle to set barriers between the vehicle and the railroad tracks in its path, and the other device being effective as a barrier to prevent by-passing of the operating means.

Another object of the invention is to provide a barrier adapted to be automatically set by rolling stock of a railroad system approaching a crossing.

Other objects and advantages will be made manifest in the following specification of embodiments of the invention illustrated in the accompanying drawings, wherein—

Figure 1 is a diagrammatic longitudinal elevation and section of the crossing control in the normal position.

Fig. 2 is a similar view showing the actuating platform of the system tripped by an automobile and the successive barriers set and as being automatically locked by a contiguous train on a railroad track.

Fig. 3 is a transverse section and partial elevation showing the actuating platform and a contiguous yielding preventer.

Fig. 4 is a sectional view transversely of the apparatus showing the yieldably mounted barrier.

Fig. 5 is a longitudinal section of a form of the apparatus which is wholly train controlled.

Fig. 6 is a transverse section on line 6—6 of Fig. 5.

Figs. 7 to 9 illustrate a slightly modified form of the invention.

The invention is shown as including a platform 2 which is pivoted as at 3 upon suitable mountings disposed in a roadway at a considerable distance from the tracks T of a railroad system, the proximity of which it is desired to give notice, effectively, to the driver of highway vehicles, more particularly motor vehicles, such as automobile A being here indicated.

The platform 2 is rigidly connected to a lever device 4 and this in turn is connected as by a link 5 to an elongated connecting or push rod 6 which, for convenience, protection and ease of operation, may be slidably mounted in a tubular guide or pipe 7. This pipe is shown as sunken below the roadway and communicates with several pits 8, 9 and 10 into and through which the push rod 6 extends. In the pit 9 is a link device 6' which is connected to the push rod 6 and also to a hingedly mounted primary barrier 11 which may be in the form of a transversely extending abutment of any suitable design. This abutment is adapted to be thrown to an upward effective position as is shown in Fig. 2 when the rod 6 is pushed longitudinally by the depression of the platform 2 as engaged by the vehicle A. In the lower position of the abutment it may be passed over freely; the abutment having a flat upper face 12 to be lowered into the plane of the highway.

The rod 6 is connected as by a link 13 to a lever arm 14 of a rock shaft 15 disposed transversely across the highway at a suitable distance between the primary barrier 11 and the railroad tracks T at the grade crossing. On the rock shaft 15 there is pivoted a second barrier or abutment 16 having a plane top 17 which latter is designed to be lowered into the plane of the highway as shown in Fig. 1.

The abutments 11 and 16 are preferably

yieldingly connected so as to tilt on their rock shafts 15 when engaged by a vehicle passing from the railroad tracks T toward and over the planes of the abutments while 5 they may be in the projected effective position as to vehicles approaching the railroad tracks.

Yielding connection may be provided in various ways, and as here shown around 10 the rock shaft 15 there is arranged a helical spring 18 secured at 19 to the shaft. The opposite end of the spring bears against the abutment section and the spring 18 tends normally to rotate with the rock shaft 15 15 and carry with it the abutment 16. In the event of a vehicle passing from the railroad tracks against the plane 17 of the abutment, the spring will yield and allow the abutment to be depressed while the lever arm 20 14 of the rock shaft may be firmly held in the angular position shown in Fig. 2 to project the abutment in effective position against vehicles running toward the tracks.

A feature of the invention consists of 25 means controlled by rolling stock on the rail tracks and for controlling the release of the barriers. The push rod 6 is normally thrust in a direction to retract the barriers from an exposed position and bring their 30 planes 12 and 17 to the road level position as by means of an expansion spring 20, though other suitable device may be used. Therefore, the function of the spring 20 is to restore the barriers to concealed position 35 as soon as the vehicle A passes off of the actuating platform 2.

The retraction of the barriers is train controlled as by means of a check device consisting here of a pneumatic mechanism 40 including a cylinder 21 disposed in the pit 10 and which operates a piston 22 connected by link 23 to the lever arm 14 of the rock shaft 15. The cylinder 21 is provided with an air inlet port 21' so that as the spring 20 45 reacts to retract the abutments the piston 22 may slide freely in its cylinder 21. However, should a train be within the given zone along the railroad tracks T it is then desirable to prevent the retraction of the 50 barriers. To that end means, here shown as electrical, are employed to control the pneumatic check device.

The electrical control means includes a 55 source of current as a battery 25 and a magnet 26 in circuit with the battery; the circuit including wires 27 attached to the railroad tracks T and the circuit is closed from track to track by the metallic elements of rolling stock when engaging the 60 electrically connected tracks within the danger zone.

As a train, for instance, closes the electrical circuit the magnet 26 is energized and actuates an armature 28 which has its up-

per end constructed and arranged to serve 65 as a valve to close the air-inlet port 21' of the pneumatic cylinder 21. Therefore, upon the approach of the train or other element of rolling stock at the grade, the valve device 28 is closed and if a vehicle A operates 70 the platform 2, the latter sets the barriers 11 and 16 and though the vehicle may pass from the operating platform the automatic restoration of the barriers, as by the springs 20, is prevented since the movement of the 75 piston 22 is so retarded in the closed cylinder 21 that the barriers will be held effective to retard or prevent the passage of the vehicle A toward the tracks.

As the railroad train clears the danger 80 zone, the circuit of the magnet 26 is broken and the valve device 28 is released and automatically opened as by a spring 29 and this permits the automatic retraction of the abutments. 85

It is desirable that the control platform 2, Fig. 3, does not extend entirely across the highway but only across one side thereof thus leaving the opposite side for the passage of vehicles in a reverse direction. But 90 it is desirable to provide means for preventing reckless vehicle drivers from passing around the operating platform 2 so as to avoid the operation and setting of the barriers. Such avoidance of the operating 95 platform may be effectively secured by the arrangement of a preventer which may consist of a guard 30 which may be pivotally mounted on the rock shaft 3 and yieldingly held in elevated position as by a spring 31. 100 The preventer 30 is shown in Fig. 1 as disposed to project obliquely in a direction toward vehicles moving along the highway toward the tracks T, while the operating platform 2 is shown, in Fig. 1, as inclining upwardly and forwardly in the path toward the tracks. Therefore, the reverse inclination of the preventer 30 serves as means for stopping vehicles approaching the tracks but provides for the depression of the preventer downwardly toward the roadway by 105 vehicles moving away from the tracks. 110

A somewhat modified form of the invention is shown in Figs. 5 and 6 in which the barrier 35 is wholly under the control, in its setting operation, of the railroad rolling stock and means are shown for projecting the barrier to effective position when a train enters the danger zone along tracks T at a grade crossing. 115

The abutment setting mechanism includes a quadrant 36 which may form a part of the abutment and is secured to a rock shaft 37 to which is attached a lever arm 38. This lever arm is connected by a link 39 to a segmental gear 40 journaled in a bearing and engaging a pinion 42 secured to the shaft of a reduction gear 43 which may con- 120 125

sist of a sprocket wheel engaging a sprocket chain 44, this in turn engaging a sprocket pinion 45. This pinion is secured to the shaft of an electric motor 46. The operating mechanism just described is arranged in a pit 48 which may have a cover 49 providing for access.

The motor 46 is served by current from a suitable source indicated as a generator G. A wire extends from this to a fixed terminal 50 spaced from which is a companion terminal 51 in a wire line 52 which is connected to a brush 53 secured to the shaft 40' of the segment 40. This brush is in electrical engagement with a contact plate 54 from which extends a wire 55 feeding the motor 46. The motor circuit is normally broken at the companion terminals 50 and 51 but is automatically closed by a cross contact 56 secured to an armature 57 of a solenoid 58 having a wire connection 59 to a source of current as a battery 60. From the battery extends a wire 61 connected to one of the tracks T, and from the other track extends a return circuit wire 62 leading to the solenoid. Thus, rolling stock passing into the danger zone will close the solenoid circuit and the cross contact member 56 will be actuated and the motor circuit closed at the contacts 50 and 51. Thereupon, the motor will be energized and the train of gears connected thereto will throw the abutment 35 to the projected position. It is desired to latch the abutment in effective position positively while the train is passing the crossing zone and yet it is desirable to cut out the motor circuit as soon as the barrier has been set.

For this purpose the quadrant 36 of the barrier is designed to be locked by a latch 65 which is shown as connected to the armature 66 of a solenoid 67 from which runs a wire 68 to a contact plate 69 positioned contiguous to the contact plate 54. These plates are so designed that while the contact brush 53 is initially traversing a portion of the plate 54, the motor circuit is closed, and during a further movement of the brush 53, it will concurrently engage contiguous portions of the plates 54 and 69, and during this moment while the motor is still running on closed circuit, the solenoid 67 will be energized and the latch 65 thrown into locking engagement with the toothed quadrant 36. As the brush 53 of the motor circuit moves off of its contact plate 54, the circuit is broken but momentum of the motor carries the brush 53 onto the solenoid circuit which includes a wire 67' connected to the generator circuit which still remains closed and holds the abutment in locked position.

As the train leaves the tracks of the danger zone, the circuit of the solenoid 58 is broken and the contact member 56 is thus released and breaks circuit at contacts 50

and 51. This deenergizes the solenoid 67, 65 which as above stated, is connected to the generator circuit. When released the barrier 35 will gravitate to its retracted position to be out of the way of traffic.

It may be desirable to prevent barriers 11 and 16 from being set when the platform 2 is depressed by a road vehicle when there is no train in the danger zone at the grade crossing. Thus, in the absence of a train, the road vehicle passing over the platform 75 could run without hindrance of the barriers toward the railroad tracks. But in the contingency that a train is in the danger zone, it is then desirable to provide for the setting of the barriers, and this mode of operation is obtained by mechanism shown in Figs. 7, 8 and 9 which is substantially similar to the mechanism of Figs. 1 and 2.

To provide for the depression of a platform 2, Fig. 7, without operation of the barrier push rod 6, this latter is shown as being broken or of sectional form, the initial section 6^a being provided with a shoulder 6^b and is connected by the link 5 to the platform 2. The main rod section 6 is adapted to be connected or coupled to the initial section 6^a to be operated thereby only in the event that there is a train in the danger zone at the crossing, and means are provided for automatically controlling the coupling of the push rod sections.

This means includes electrical apparatus involving preferably a normally closed circuit 70 including a magnet 71 normally holding open a circuit switch 72 in the circuit of the battery 25 and which circuit includes the magnet 26 controlling the pneumatic check valve 28. The switch 72 is connected by a line 73 leading to a magnet 74 which is shown as arranged in a pit through which the push rod passes and in which pit there is provided a latch 75 here shown as connected to the end of the push rod 6 which is contiguous to the shoulder 6^b. The latch 75 is provided with an armature 76 attractive by the magnet 74 when the circuit of the battery 25 is closed by the switch 72. The switch 72 which, as above stated is normally opened by the closed circuit 70, will be released by the entry of a train on the tracks T, Fig. 7, which train will cause the shortening of the circuit of the magnet 71 which circuit includes a battery 70^a from which runs the short circuit line 70^b. The circuit 70 is shown as connected to one of the tracks T and the short circuit wire 70^b to the other track, and therefore the rolling stock on the tracks will short the circuit of the battery 70^a and the magnet 71 will be deenergized. This will permit the closing of the switch 72 as by its spring 72^a, whereupon the latch 75 will be drawn to the effective position in front of the shoulder 6^b.

on the initial rod section 6^a. Therefore, at this arrangement of the parts, if a vehicle depresses the platform 2, then the rod 6 becomes effective to set the barriers 11 and 16. These barriers will be maintained in effective position so long as the valve device 28 is in closing relation to the pneumatic check cylinder 21. From the above it will be seen, therefore, that the platform 2 may be depressed and will actuate the rod section 6^a without shifting the main rod 6, and a vehicle may then pass without obstruction over the crossing.

The platform is shown in Fig. 7 as being restored to uppermost position by a spring 80 connected to a piston rod 81 which in turn is connected to the link 5. The piston rod 81 has a piston 82 operating in a dash pot 83 which will permit the rapid downward movement of the platform 2, but will check the action of the spring 80 in restoring the platform to elevated position for the purpose of preventing the platform from rising too quickly and engaging the rear wheels of the actuating road vehicle, the front wheels of which trip down the platform.

Further embodiments, modifications and changes may be resorted to within the spirit 30 of the invention as here claimed.

What I claim is:

1. In combination with railway tracks at a grade crossing, road vehicle operated barrier means adapted to be exposed across a road or highway approaching the railway tracks to impede vehicle traffic on the highway, and means under control of railway rolling stock for controlling the operation of the barrier means.

40 2. In combination with railway tracks at a grade crossing, road vehicle operated barrier means sunk in and adapted to be exposed across a road or highway approaching the railway tracks to impede vehicular traffic on the highway, and electrical means under the control of railway rolling stock for controlling the operation of the barrier means.

50 3. In combination with railway tracks at a grade crossing, road vehicle operated barrier means adapted to move from a clear position in a roadway to a barricading position, means for operating the barrier means to render the same effective, and railway rolling stock controlled means for holding the barrier means in effective position.

60 4. In combination with railway tracks at a grade crossing, road vehicle operated barrier means adapted to move from a clear position in a roadway to a barricading position, means for operating the barrier means to render the same effective, and railway rolling stock controlled means for holding the barrier means in effective position, said

controlled means becoming inoperative 65 when the rolling stock clears the danger zone.

5. In combination with railway tracks at a grade crossing, road vehicle operated barrier means adapted to move from a clear 70 position in a roadway to a barricading position, means for operating the barrier means to render the same effective, and railway rolling stock controlled means for holding the barrier means in effective position, said 75 controlled means including an electrical circuit having connections to the railway tracks and which circuit is closed when the rolling stock engages the electrically connected tracks.

6. In combination with railway tracks at a grade crossing, barrier means adapted to be exposed across a road or highway approaching the railway tracks to impede vehicular traffic on the highway, means under control of railway rolling stock for controlling the operation of the barrier means, and a road vehicle actuated means for setting the barriers.

7. In combination with railway tracks at a grade crossing, barrier means adapted to be exposed across a road or highway approaching the railway tracks to impede vehicular traffic on the highway, means under control of railway rolling stock for controlling the operation of the barrier means, a road vehicle actuated means for setting the barriers, and means for automatically retracting the barriers when released by the railway controlled means.

8. In combination with railway tracks at a grade crossing, barrier means adapted to be exposed across a road or highway approaching the railway tracks to impede vehicular traffic on the highway, means under control of railway rolling stock for controlling the operation of the barrier means, and a road vehicle actuated means for setting the barriers, the barriers being yieldable under pressure in one direction to permit the 105 passage of road vehicles.

9. In combination with railway tracks at a grade crossing, barrier means adapted to be exposed across a road or highway approaching the railway tracks to impede vehicular traffic on the highway, means under control of railway rolling stock for controlling the operation of the barrier means, and a road vehicle actuated means for setting the barriers, the barrier means being operative to automatically return to concealed position unless prevented by the railway control means.

10. In an apparatus for grade crossing controls and adapted to retard advance of a road vehicle to railway tracks at a grade crossing, barrier means, a vehicle operated platform for actuating the barrier means to

render the same effective, and a preventer contiguous to the said platform to prevent by-passing of vehicles around the platform.

11. In an apparatus for grade crossing controls and adapted to retard advance of a road vehicle to railway tracks at a grade crossing, barrier means, a vehicle operated platform for actuating the barrier means to render the same effective, and a preventer contiguous to the said platform to prevent by-passing of vehicles around the platform, the preventer being yieldable to permit the passage of vehicles from one direction.

In testimony whereof I have signed my name to this specification.

DALLAS H. SMITH.
